UNITED STATES PATENT OFFICE

2,534,969

SURFACE WORKING MACHINE

Carl Hauser, Steffisburg, Switzerland

Application August 14, 1946, Serial No. 690,569
In Switzerland August 17, 1945

1 Claim. (Cl. 51—176)

1

The present invention relates to a surface working machine and, particularly, to a floor surfacing machine of the rotary type employable for cleaning, waxing, polishing and grinding floor surfaces.

It is an object of the invention to provide means for mounting in a portable housing and in a very compact manner a horizontal cylindrical drum for rotation and for detachably connecting to said drum various working or cleaning devices or tools.

Another object of the invention is to provide means facilitating accommodation of an electric motor within said horizontal drum for driving the same.

A further object of the invention is to provide means making it possible to associate a dust catcher or collector device with said housing, which may be equipped with a suction device adapted to be actuated by said electric motor.

Still a further object of the invention is the provision of a frame with front and rear wheels carrying said housing and said drum in adjusted position for varying the pressure imparted by the working tools to the floor surface.

With the foregoing and other objects in view, the invention will be more fully described hereinafter. An embodiment of this invention is shown in the accompanying drawings in which:

Fig. 1 is a side elevation of the machine according to the invention with the side wall of the housing removed therefrom and the upper portion of the operating handle broken away.

Fig. 2 shows a longitudinal vertical section taken on the line 2—2 in Fig. 1.

Fig. 3 is an end view of the drum and the driving gear adapted to rotate the same, the drum being equipped with a cleaning device of steel shavings.

Figs. 4 to 6 are fragmentary side views of various working devices, drawn to a larger scale.

Fig. 7 is a vertical sectional view of a dust suction device.

Fig. 8 is a horizontal sectional view of the suction device of Fig. 7, and

Fig. 9 shows a cross section through the dust suction compartment.

In the construction shown in the drawings, an electric motor represented by its motor frame 1 is arranged within a hollow horizontal cylindrical working drum 7 and has a shaft 2 which substantially coincides with the drum axis. Shaft 2 carries at both ends a bevelled friction wheel 3, preferably provided with a rubber surface. Each friction wheel 3 drives three similar but inversely

2

bevelled friction wheels 5 which are arranged on both end walls respectively, of the motor frame 1 and rotatably mounted on codirectional pins 4 screwed into the aforesaid end walls of the motor frame. Each set of friction wheels 5 acts upon a respective bevelled rubber ring 6, said rings 6 being secured to the inner surface of the working drum 7 near the respective lateral edges thereof. The cylindrical drum 7 is adapted to removably receive various working tools or devices 8 which belong to the machine and may be interchangeably mounted thereon. There are devices in the form of steel shavings, of steel wire brushes, fibre brushes, hair brushes, and the like, the working surfaces thereof being interrupted at regular intervals as shown in Fig. 3. Each working device is equipped with a clamping means 16 illustrated in Figs. 1, 4 and 5, by means of which the working tool may be readily attached to and retained on the outer cylindrical drum surface. This drum surface may be covered by a grinding cloth which is pasted thereon as shown in Fig. 6. The two heads or ends of the drum 7 are formed by two stationary supporting disk-shaped plates 11 by which the friction gears and the electric motor are covered up in the drum and to which the frame 1 of the electric motor is secured by means of screws 12. A grooved pulley 9 adjacent the outer face of disk 11 (shown in Figs. 1 and 2) is connected for rotation through an aperture in this disk with one of the bevelled friction wheels 5. Different flat iron frame bars 13 and 19 which are secured to the disks 11 carry and connect the drum 7 to the housing 36 which is made of sheet metal and which includes a dust collector compartment 34. The four rollers or wheels 21 are each supported in a fork 20. The fork of the two fore-rollers is connected to a flat iron bar 14 screwed at 14a to the disk 11 and are adjustable in two positions determined by separate threaded openings 25a adapted for the engagement of the screw 25 carried by the bar 14. A stop 24 on the disk 11 limits the swinging movement of the bar. The fork of the two rear rollers is connected at 15a by means of a linkage which consists of flat iron bar 26 and arm 28a to an adjusting lever 15 which is pivotally mounted at 15b on the bar 13. Lever 15 is operable to swing about pivot 15b for the engagement of a detent 16a with one of the spaced grooves 16b on curved arm 16. Lever 15 and the aforesaid linkage form part of the height-regulating means for spacing the drum surface from a floor F to be worked upon. A hollow axle 28 screwed into each disk 11 projects therefrom in axial alignment with the

drum axis. The surface working machine has an operating handle of which only the fork 17 is shown in the drawings. This fork 17 is pivotally mounted with its two perforated ends on the two hollow axles 28. The rollers 21 together with the two disks 11 and the intermediate fixing bars constitute the frame or under carriage on which the motor driven working drum and the housing are mounted.

The dust collector compartment 34 includes a suction or ventilator device comprising two horizontal suction tubes 23 symmetrically arranged in axial alignment, which have a radial inlet and an axial outlet opening as shown in Figs. 7 to 9. Two fans 29 are disposed in the outlet openings and mounted on a common shaft driven by a grooved pulley 18 which extends outside the tubes 23 and is coupled for rotation with the pulley 9 by means of a transmission belt 22 running in the grooves of the pulleys. A metal sheet 30 (Fig. 8) is fixed to the dust collector compartment 34 to divide the dust stream and lead it to the inlet openings of the suction tubes 23. The dust sucked by the fans 29 falls down into a container 27 which forms the lower part of the dust-collector compartment 34 and is detachably hinged thereto. The container 27 is equipped with a handle 38. A partition 32 extending downward in the upper part of the dust collector compartment 34 is provided to guide the dust into the container 27, while the flow of air is deflected and passes upwards through a first filter 33 into a chamber behind the partition 32 and then through a second filter 31 on the wall of the dust-collector 34 to the outside atmosphere (Fig. 9).

Fig. 1 shows the machine drum equipped with a scrubbing device or tool comprising batches of steel shavings. In order to use the machine for surface grinding, the scrubbing equipment is removed from the drum surface to uncover the grinding cloth surface of the same and the supporting bars 14 of the forerollers or wheels are then swung about pivot 14a from the lower stop 24a to abut against the upper one 24 while the screw 25 engages the corresponding upper threaded hole 25a. The friction generated by the respective rotating working tool on the floor surface F may be varied by lifting or lowering the drum 1 by means of the adjusting lever means 15 arranged on both sides of the machine and having their free ends coupled by a cross handle bar (not shown). The motor cable 35 extends along the operating handle and fork 17 where it is fixed by means of clips 37 and leads through one of the hollow axles 28 to the frame 1 of the electric motor. When the machine is operated, the electric motor drives the working drum 7 through the friction gears 3-5 and simultaneously the ventilators 29 through the transmission pulleys 9 and 18. The housing 36 covers all motor driven parts of the machine and preferably consists of detachable parts which may be removed separately.

There may be no suction device in the dust catcher and the opening to the dust catcher may be so constructed that the dust is centrifuged into the dust catcher owing to the rotation of the working drum, while the revolved air flows through filters to the outside.

It can thus be seen, that there has been provided according to the invention a surfacing machine adapted for the use of a plurality of interchangeable tools on the surface of the drum of the machine. This drum is rotatable and hollow and accommodated in a casing which is equipped with front wheels and rear wheels; an electric motor positioned in said hollow drum and adapted to impart rotary movement to the latter, suction means in driving connection with said motor and disposed at a location above the axis of said drum within said casing, height-regulating means spacing said drum surface from said floor to be worked upon, said height-regulating means including hand-operated adjusting lever means pivotally mounted on the casing and a linkage connecting the adjusting lever means to the rear wheels, said linkage being pivoted to the casing above said rear wheels, whereby upon operation of said adjusting lever means said linkage swings said rear wheels to thereby regulate the distance of the axis of said drum with respect to the floor surface, and means connected to said front wheels for changing the relative position of the axis of the latter to that of said rear wheels.

I claim:

In a floor surface working machine having a rotatable and hollow drum accommodated in a casing which is equipped with front wheels and rear wheels; an electric motor positioned in said hollow drum and adapted to impart rotary movement to the latter, suction means in driving connection with said motor and disposed at a location above the axis of said drum within said casing, height-regulating means spacing said drum surface from said floor to be worked upon, said height-regulating means including hand-operated adjusting lever means pivotally mounted on the casing and a linkage connecting the adjusting lever means to the rear wheels, said linkage being pivoted to the casing above said rear wheels, whereby upon operation of said adjusting lever means said linkage swings said rear wheels to thereby regulate the distance of the axis of said drum with respect to the floor surface, and means connected to said front wheels for changing the relative position of the axis of the latter to that of said rear wheels.

CARL HAUSER.
